Fig. 4.

UNITED STATES PATENT OFFICE

BENJAMIN H. FLYNN, OF ALEXANDRIA, LOUISIANA

HIGHWAY CONSTRUCTION OVER-PASS

Application filed June 5, 1931. Serial No. 542,430.

In constructing concrete and other highways with present-day equipment, the grade is prepared in a great number of instances by a grading machine extending throughout the width of said grade and traveling on side forms or track rails, and the prepared grade is used as a roadway for the trucks which haul the highway materials back to the paving machine or to the labor employed for spreading said materials. The grading machine completely blocks the grade when in operation and as it is impracticable to swing said machine aside each time a truck must pass, and it is often impossible to drive the trucks around it, it is customary to use the grader only at night when no hauling of materials is being done, and to swing it from the grade and leave it idle when hauling is to be resumed. Such procedure of course necessitates not only the expense and inconvenience of employing both day and night shifts, but necessitates that side forms or rails be kept on hand in large quantities, for they must be laid such a distance as to allow sufficient grading for a day's construction. Then too, even though the grading machine may leave the grade in perfect condition, the trucks soon badly rut said grade and impart to it an undesirable varying density.

My invention aims to make provision whereby the trucks do not use the prepared grade but operate only in front of the grading machine, and it provides for carrying the highway materials from the trucks over said grading machine while the latter remains on the grade, the materials being carried on back to the paving machine or to the construction gang after passage over the grader. Hence the grading machine may be operated during the day as the job progresses, without interfering with the delivery of materials, it is only necessary to keep a relatively few lengths of forms or track rails ahead of said grading machine, and the truck will not injure the prepared grade.

The provision for passing the materials over the grading machine, is preferably mounted on a frame provided with wheels to run upon the above-named side forms or track rails, but it is not essential that said

frame be supported by the track rails or side forms, as it might in some instances be provided with ground wheels or caterpillar treads, or might be directly carried by the grading machine. Moreover, while the primary intent is to convey the construction materials over a grading machine, it is to be understood that the invention is equally adaptable for conveying materials over any other machine or obstruction on the grade.

The provision for carrying the materials on back from the over-pass and the grading machine, to the paving machine or the construction gang, preferably consists of a motor-driven shuttle car operating upon the side forms or rails. Here again however, the car need not be supported by the side forms or rails but could be provided with ground wheels or endless treads of such nature as to run upon the finished grade without injuring the latter.

One practical embodiment of the invention has been illustrated in the accompanying drawings and will be rather specifically described, with the understanding however that numerous variations may be made within the scope of the invention as claimed.

Fig. 1 is a side elevation illustrating highway construction equipment in accordance with the invention.

Fig. 2 and Fig. 3 are vertical transverse sectional views on lines 2-2 and 3-3 respectively of Fig. 1.

Fig. 4 is an enlarged section showing the car and portions of its supporting rails, used for carrying the materials over the grading machine or other obstruction.

Fig. 5 is a sectional view on line 5-5 of Fig. 4.

On the drawings, (Fig. 1) 10 denotes a diagrammatic showing of a grading machine having wheels 11 running upon side forms or rails 12, and 13 denotes a rotary cutter of said machine 10 for preparing the grade 14 upon which a highway is to be constructed. Behind the grading machine, I have diagrammatically illustrated the skip 15 of a conventional paving machine which is supported in the usual way upon the finished grade, the paving machine and the machine

10 being of course movable along as their work progresses.

A portable frame 16 extends over, forwardly from and rearwardly from the machine 10 and is provided with an open top dump car 17 for conveying the construction materials from trucks in front of the frame 16, over the machine 10 to the rear end of said frame. A shuttle car 18 of motor driven nature, is either movable along the side forms or rails 12, or along the grade 14, between the machine 10 and the paving machine, said shuttle car having a dump body 19. When the car 18 is positioned as seen in Fig. 1, the car 17 may discharge its load into the body 19, said car 17 having a rear gate 17' for this purpose. The car 18 is then used to convey the materials on back to the paving machine or to the construction gang. When a paving machine is being used, the body 19 may well dump its load directly into the skip 15.

It will be observed that the trucks which discharge their loads into the conveying car 17, never reach the finished grade 14 and consequently cannot injure the same. Moreover in view of the fact that the material can be carried over the grading or other machine 10, both hauling and paving may be carried on during the day instead of grading at night sufficient for a day's run and paving the graded portion on the following day. Moreover, as the grading machine 10 may be advanced comparatively short distances at a time, when using the equipment herein provided, it is only necessary to keep comparatively few lengths of the side forms or rails 12 laid ahead of said machine and hence it is unnecessary to keep such a large number of said side forms or rails on hand.

The frame 16 embodies a front transverse truss frame 20, a rear transverse truss frame 21, and an intermediate transverse truss frame 22, all of said frames having supporting wheels 23 which are flanged when they are to run upon side forms or rails 12. The front frame 20 is of arched form, allowing the car 17 to pass under its crown portion, but the frames 21 and 22 need not be so arched, as the car passes over them. These frames 21 and 22 are disposed to abut the front and rear of the machine 10, so that as said machine travels, the frame 16 will also travel.

The frames 20, 21 and 22 are tied together by longitudinal bars 23' and also by a longitudinal trackway 24, said trackway being secured upon the frames 21 and 22 and secured to the legs of the frame 20. This trackway embodies a horizontal portion 25 extending over the machine 10, a portion 26 which inclines to the front end of said portion 25, and a downturned portion 27, the latter having stops 28 at its ends. The trackway 24 also embodies a substantially horizontal front

portion 29 pivoted at 30 to the lower end of the portion 26, for vertical swinging. The car 17 is provided with flanged wheels 31 traveling upon the trackway 24 and when this car is upon the portion 29 as seen in Figs. 1 and 5, trucks T may dump their loads into it. The loaded car 17, when moved rearwardly along the trackway 24 to the position shown in dotted lines in Fig. 1, may dump directly into the body 19 of the shuttle car 18.

The body 32 of the car 17, is preferably provided with an end gate 33 to swing downwardly onto the ground as seen in Figs. 1, 4 and 5, allowing the trucks to back partly into said body when dumping, as seen in Fig. 4. When the body 32 receives the weight of a truck and its load, the pivoted front portion 29 of the trackway 24, of course depresses and the sills 32' of said body then rest solidly upon the ground and while the truck is dumping and holding the car 17, the rest of the machine may continue to advance. When only the unloaded car is supported by the trackway portion 29, the latter is swung upwardly and the car 17 elevated clear of the ground, by means of appropriate suspenders 34 which connect said portion 29 with the front truss frame 20, said suspenders embodying springs 35. These springs of course stretch when the trackway portion 29 must depress onto the ground.

Any preferred means may be employed for moving the car 17 along the trackway 24. For this purpose, I have shown an arrangement of cables 36, sheaves 37 and motor-driven drums 38, the frame 16 being provided at suitable points with transverse supporting rollers 39 for certain reaches of said cables. The foremost sheave may well be carried by a forwardly projecting arm 40 secured to transverse bars 41 embodied in the construction of the trackway 24.

When the frame 16 is constructed to travel upon side forms or rails 12, provision is preferably made for adjusting the wheels 23 along their axles 42, or for otherwise adjusting the frame to travel upon forms or rails spaced different distances apart, according to the width of the highway being constructed. The same is true of the shuttle car 18.

I claim:—

1. In highway construction equipment, a mobile machine which obstructs a highway grade to passage of road trucks, and means for receiving highway materials from road trucks in front of said machine and conveying said materials over the machine and on rearwardly beyond said machine to the required destination.

2. In highway construction equipment, the combination of a mobile machine which obstructs a highway grade to passage of trucks, a frame extending over, forwardly from and

rearwardly from said mobile machine and adapted to be advanced therewith, conveying means mounted on said frame for carrying highway materials from the front to the rear 5 of said frame, and additional conveying means behind said machine adapted to receive the materials from the first named conveying means and to carry them on rearwardly beyond said machine to the required 10 destination.

3. In highway construction equipment, the combination of a mobile machine which obstructs a highway grade to passage of trucks, a frame extending over, forwardly from and 15 rearwardly from said mobile machine and adapted to be advanced therewith, conveying means mounted on said frame for carrying highway materials from the front to the rear of said frame, and a shuttle car behind said 20 machine adapted to receive the materials from said conveying means and to convey them on rearwardly to the required destination.

4. In highway construction equipment, the 25 combination of parallel track rails, a machine movable upon said rails, a frame extending over, forwardly from, and rearwardly from said machine and adapted to be advanced therewith, conveying means mounted 30 on said frame for conveying materials from the front to the rear of said frame, and a shuttle car movable upon said rails behind said machine, said shuttle car being adapted to receive the materials from said conveying 35 means and to carry them on rearwardly to the required destination.

5. In highway construction equipment, the combination of parallel track rails, a machine having wheels upon said rails, a frame extending over, forwardly from, and rearwardly from said machine, said frame having supporting wheels independent of the first-named wheels and engaging said rails to allow advance of the frame with the machine, 45 conveying means mounted on said frame for conveying materials from the front to the rear of said frame, and a shuttle car movable upon said rails behind said machine, said shuttle car being adapted to receive the materials 50 from said conveying means and to carry them on rearwardly to the required destination.

6. In highway construction equipment, a mobile frame adapted to extend over, forwardly from and rearwardly from a mobile 55 machine, and conveying means mounted on said frame for conveying materials from end to end of said frame.

7. In highway construction equipment, a 60 wheeled frame adapted to extend over, forwardly from and rearwardly from a wheeled machine, the wheels of said frame being independent of the wheels of the machine over which the frame extends, and conveying means mounted on said frame for conveying 65 materials from end to end of said frame, said

frame having means for connecting it with the machine to advance therewith.

8. In highway construction equipment, a mobile frame adapted to extend over, forwardly from and rearwardly from a machine, and conveying means mounted on said frame for conveying materials from end to end of said frame, said frame embodying two spaced transverse members adapted to abut the front and rear of the machine respectively, whereby the frame and machine may be bodily advanced. 70 75

9. In highway construction equipment, a mobile frame adapted to extend over, forwardly from and rearwardly from a machine, and conveying means mounted on said frame for conveying materials from end to end of said frame, said frame embodying two spaced transverse truss structures adapted to abut the front and rear of the machine respectively, whereby the frame and machine may be bodily advanced. 80 85

10. In highway construction equipment, a portable frame, a trackway mounted on said frame, said trackway embodying an elevated portion, a portion inclined to said elevated portion and a substantially horizontal portion leading to the lower end of said inclined portion, and conveying means movable along said trackway for carrying materials from said horizontal trackway portion to the end of said elevated trackway portion. 90 95

11. In highway construction equipment, a portable frame, a trackway mounted on said frame, said trackway embodying an elevated portion, a portion inclined to said elevated portion, and a substantially horizontal portion leading to the lower end of said inclined portion, a dump car movable along said trackway and having an open top body into which material may be dumped when the car is on said horizontal portion of the trackway, and means for moving said car from end to end of said trackway. 100 105

12. In highway construction equipment, a portable frame, a trackway mounted on said frame, said trackway embodying an elevated portion, a portion inclined to said elevated portion, and a substantially horizontal portion pivoted for vertical swinging to the lower end of said inclined portion, a dump car movable along said trackway and having an open top body into which a truck may dump when the car is on said horizontal portion of the trackway, means for moving said car from end to end of said trackway, and means for upwardly swinging said horizontal portion of said trackway. 110 115

13. In highway construction equipment, a portable frame, a trackway mounted on said frame, said trackway embodying an elevated portion, a portion inclined to said elevated portion, and a substantially horizontal portion pivoted for vertical swinging to the lower end of said inclined portion, a dump 120 125 130

car movable along said trackway and having an open top body into which a truck may dump when the car is on said horizontal portion of the trackway, means for moving said car from end to end of said trackway, and spring means acting on said horizontal portion of said trackway and active to hold it slightly above the ground when sufficiently free of weight.

10 14. In highway construction equipment, a portable frame, a trackway mounted on said frame, said trackway embodying an elevated portion, a portion inclined to said elevated portion, and a substantially horizontal portion leading to the lower end of said inclined portion, a dump car movable along said trackway and having an open top body into which material may be dumped when the car is on said horizontal portion of the trackway, said body having an end gate adapted to swing downwardly onto the ground to allow backing of a truck partly into said body when said car is on said horizontal portion of the trackway, and means for moving said car from end to end of said trackway.

15 15. A structure as specified in claim 14; said substantially horizontal portion of said trackway being mounted for vertical swinging, spring means exerting a normal upward force on said horizontal trackway portion to hold the latter and the dump car free from the ground and to permit depression thereof when a truck backs into said dump car, said dump car having supporting means to rest upon the ground when said car is under the weight of the truck, said supporting means projecting below said horizontal trackway portion and preventing the latter from contacting with the ground, thereby allowing the equipment to advance while the truck is dumping.

20 16. In highway construction equipment, a mobile machine, a car adapted to receive a load from a truck in advance of said mobile machine and adapted to carry said load to a point behind said machine, and guiding means for said car connected with said machine to progress with the latter, said car having a portion adapted to rest upon the ground while receiving a load from the truck, said guiding means being then adapted to move forwardly with the machine while the car is held against movement by the truck.

25 In testimony whereof I affix my signature.
BENJAMIN H. FLYNN.
